8 Sheets-Sheet 1

Fig. 1. A detailed cross-sectional view of a mechanical assembly, likely an engine or pump. The drawing shows various components including a cylinder, piston, connecting rod, crankshaft, and valves. Numerous parts are labeled with numbers such as 1, 2, 117, 136, 138, 135, 116, 111, 146, 145, 149, 18, 95, 102, 113, 101, 132, 144, 143, 99, 50, 53, 55, 56, 58, 244, 245, 223, 13, 51, 11, 15, 16, 17, 18, 19, 100, 110, 130, 131, 132, 133, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, UNITED STATES PATENT OFFICE

LIONEL A. SCHMIDT, OF POUGHKEEPSIE, NEW YORK, ASSIGNOR TO PENNSYLVANIA GASOLINE DRILL COMPANY, A CORPORATION OF DELAWARE

IMPACT TOOL

Application filed July 14, 1927. Serial No. 205,681.

My invention relates to a gasoline operated drill, hammer or similar impact tool or device in which a unitary piston or piston-hammer is reciprocated within a cylinder on the principle of a two-cycle internal combustion motor to impart at the end of its power stroke a blow to a tool, such as a drill or drill-bit, a riveting tool or a digging tool, the power to effect the reciprocation of said piston-hammer being derived from the combustion of a gasoline explosive mixture in one end of the cylinder.

The structure forming the subject-matter of my invention includes a unitary cylinder comprising three coaxially aligned parts, rigidly secured together and within which the impact-piston or piston-hammer is reciprocated on the principle of a single-acting two-cycle internal combustion engine, insofar as air is drawn by the piston or piston-hammer through a carburetor into a mixing and transfer chamber on the non-working or compression stroke of the piston-hammer; is transferred, under pressure at the end of the working stroke to the combustion end of the cylinder to expel the products of combustion remaining in the cylinder from the previous working stroke; is compressed within the combustion chamber during the non-working or compression stroke and is exploded at the end of the compression stroke by a suitable ignition device or system to impel the piston or piston-hammer forwardly to effect the working stroke and to produce an impact of the piston-hammer against a tool appropriately mounted in or at the end of the cylinder. The present invention relates to the type of percussion tool which forms the invention of Letters Patent of the United States Number 1,508,623, granted September 16, 1924, to Charles Stuart Somervell, and comprises certain improvements therein, whereby the construction is somewhat simplified, the operation of the mechanism rendered more efficient and the structure is more durable.

In percussive tools of this type the piston or piston-hammer is reciprocated rapidly and the blow upon the tool or stripe-pin is heavy and sharp, with the result that the parts of said drill to which the blows are imparted or

communicated and by which the shocks are absorbed, must withstand such strains and vibrations over a relatively long period of time.

The explosion end of the cylinder in this type of tool tends to become very hot, for the weight of a water-cooling system for the cylinder would greatly detract from the utility of the drill as a portable mechanism. The cylinder and the parts heated thereby must be air cooled by mere radiation, for a fan or other means for circulating a current of air over and around the cylinder would seriously interfere with the manipulation of the tool and add to the weight of the tool. But the air cooling of the cylinder and piston by conducting the heat of combustion by static radiation is a relatively inefficient method of reducing the temperature of the metal cylinder with the result that, the piston and the explosion end of the cylinder and the cylinder head are required to operate at much higher temperatures than those to which ordinary internal combustion engines are subjected. It is, therefore, one of the objects of the present invention to provide a cylinder construction wherein as much as possible of the heat of the piston head is conducted directly to the walls of the combustion chamber, to provide those walls with as great a heat conducting and dispersing area as is possible, and to make that portion of the cylinder of a steel which has been heat-treated so that it will withstand and operate satisfactorily under high temperature conditions.

A further object of my invention is to heat-treat that portion of the cylinder which is subjected to the sharp, rapid impact of the piston-hammer and in such a manner as to make it stand up without crystallization for a long period of time. The portion of the cylinder forming the combustion or explosion chamber and the part of the cylinder which is subjected to the severe shocks and blows above-mentioned are located at opposite ends of the unitary cylinder structure and upon the intermediate portion is mounted a rotor, preferably concentric with the axis of the cylinder and of the piston-hammer, as shown in the Somervell patent above referred

to. It is through this intermediate portion that the cross-head carried by the piston-hammer projects and in which the cross-head is slidingly mounted for reciprocation, and the ends of the cross-head are in engagement with the cam carried by the said rotor by means of which the reciprocatory rectilinear motion of the piston-hammer is converted into the rotary movement of the rotor to effect the return or compression stroke of the piston. This intermediate portion is subjected to torsional strains about its axis, in addition to being required to absorb some of the shocks imparted to the impact end of the cylinder and some of the heat conveyed thereto from the combustion end of the cylinder. It is, therefore, a further object of my invention to heat-treat the metal of said intermediate portion in such a manner as to make it capable of best withstanding the peculiar strains to which it is subjected.

A further object of my invention is to provide a construction wherein that portion of the cylinder, including the combustion chamber and the adjacent intermediate portion upon which is mounted the rotor, may be used without any change whatever in their construction with either of two different types or kinds of impact sections; (1) an impact section providing a fuel intake and transfer chamber and an air compression chamber and (2) another impact section providing only a fuel intake and transfer chamber.

A further object of my invention is to provide a construction wherein a uniform explosive mixture may be formed and maintained during the continuous action of the drill. It is the object of my invention to draw the air for the explosive mixture through the carburetor into the mixing chamber and then to discharge the mixture at the end of the working stroke out through the same port over or through the carburetor but without adding to the mixture more gasoline or similar fuel, with the result that substantially all the air is discharged from the cylinder during each stroke and out through the same port by which it entered so that a fresh supply of uniform explosive mixture is drawn into and delivered from the mixing and transfer chambers on every complete reciprocation of the piston-hammer.

A further object of my invention is to provide adequate means to air-cool the piston-head, the cylinder head, and the walls of the explosion chamber without substantially adding to the weight of the drill as a whole.

A further object of my invention is to provide replaceable means carried by the piston rod to adjust the fluid capacity of the fuel mixing chamber and to correspondingly regulate the amount of air which is drawn into the chamber on every non-working stroke of the piston-hammer.

A further object of my invention is to pro-

vide a construction wherein the section of the cylinder forming the explosion chamber and the cylinder head therefor may be readily removed and replaced upon the other parts of the mechanism when assembled to expose the piston-head as, for example, for the replacement of piston rings, without disturbing in the least the assembly or adjustment of the other parts of the device except possibly the upper ends of the guard rods or frame by which the device may be carried from place to place and steadied during the operation of the device.

A further object of my invention is to provide the cylinder of an impact tool of the type above described, with three chambers in each of which is a piston-head of the piston-hammer, the three chambers forming respectively the explosion chamber, the air compression chamber and the fuel mixing and transfer chamber, without necessitating the use of a stationary cylinder head between the piston-head and the hammer head.

A further object of my invention is to so position the carburetor with respect to the cylinder and the guard frame that it is shielded or protected from accidental knocks and the injury likely to result therefrom, the carburetor being positioned below the overhanging oil pan and between the rods or bars which support the knee-plate, and behind the knee-plate.

A further object of my invention is to provide the housing for the flywheel or rotor element with a receptacle within which is fitted and retained an ignition unit comprising the induction coils and condenser, whereby said unit may be located close to the spark plug and electrically connected therewith by a short insulated wire which is not in the way of the operator and which is not subjected to the rubbing, bending or flexing that a long connection for the purpose would be subjected.

A further object of my invention is to dispose substantially all the bolts or fastening means by which the parts are connected together with their longitudinal axes substantially parallel to the axis of the cylinder, so that the severe shocks and blows to which the parts are subjected and which are in the main in a direction parallel to the axis of the cylinder, may be taken up by the bolts longitudinally, thereby avoiding the tendency of the fastening means to shear when subjected to such stresses.

The severe vibration to which the cross-head and the piston-hammer are subjected makes it difficult to mount the cross-head in the piston-hammer in such a way that it does not creep slightly longitudinally and loosen as a result of such stresses. It is the object of my invention to prevent such motion or loosening of the cross-head by tightly fitting it into a cylindrical passage through the pis-

ton-hammer with a spline to prevent the rotation of the cross-head about its axis and to hold it in position by a slowly tapering pin tightly fitting a corresponding tapered hole

5 passing transversely through the piston-hammer and forming a tangential groove in the surface of the cross-head. When said pin has been tightly driven into said tapering hole it will not loosen by vibration and will 10 prevent any longitudinal movement whatever of the cross-head in the piston-hammer.

Further objects of my invention will appear in the specification and claims below.

In the drawings forming a part of this 15 specification and in which the same reference characters are employed throughout the various views to designate the same parts,

Fig. 1 is, in the main, a vertical longitudinal section through the important operative 20 parts of the drill structure with the gasoline supply tank, carburetor, supporting rods or frame by which the tool may be handled or manipulated and operated, and the knee-plate shown in elevation.

25 Fig. 2 is a side elevational view of the rear side of the tool shown in Fig. 1 with the knee-plate removed.

Fig. 3 is a top plane view of the top plate or cover and the supporting handles or bars 30 attached thereto.

Fig. 4 is a vertical sectional view through the timing mechanism and a diagram of the electric ignition circuit connected thereto.

Fig. 5 is a vertical section through the carburetor.

Fig. 6 is a side elevational view but with a vertical section taken through the gasoline needle valve portion thereof said section being on the line 6—6 of Fig. 5.

40 Fig. 7 is a horizontal sectional view through the cylinder and through the air pressure controlling valve for the air compression chamber, said section being substantially on the line 7—7 of Fig. 2.

45 Fig. 8 is a vertical sectional view on the line 8—8 of Fig. 7.

Fig. 9 is an end view of the pressure controlling valve, the lower part being broken away or sectioned to show the dirt and dust 50 deflector over the air inlet port or opening.

of the lower ring or washer of the said chuck with that part of the chuck which passes through said ring shown in transverse cross-section.

Fig. 18 is a side elevational view, partly 70 in section, of the lower ring or washer shown in Fig. 17.

Fig. 19 is a detail, mostly in section, showing the cross-head pin passing through the cross-head supporting section, the rollers, the manner of securing the cross-head pin rigidly in the cross-head supporting section of the piston-hammer and the rollers mounted and retained on the cross-head.

Fig. 20 is a fragmentary view of the cross-head supporting section with the cross-head 80 in cross-section, the section being taken at right angles to that shown in Fig. 19.

Fig. 21 is a transverse sectional view of the piston rod with the split sleeve clamped 85 thereto for determining the capacity of the air compression chamber.

Fig. 22 is a top plan view and Fig. 23 a side elevational view of one of the springs of the chuck.

Fig. 24 is a horizontal cross-sectional view 90 of a part of the explosion section of the cylinder, showing the exhaust ports and the deflectors secured on opposite sides thereof; and

Fig. 25 is a longitudinal sectional view, 95 similar to Fig. 1, of a modified construction.

Referring first to the construction illustrated in Fig. 1, the main cylinder 1 is preferably composed of three generally cylindrically-shaped alined portions, namely, the combustion or explosion end or section 2, the cross-head guide and rotor supporting section 3, which is an intermediate section, and the fuel intake and compression section 100 which is the lower section 4.

In the form of my invention illustrated in Fig. 1, the fuel intake and compression end or section may substantially comprise two parts, namely, (1) the fuel mixing and transferring chamber 5 and (2) the air compression chamber 6.

105 The piston-hammer 7 is a unitary piece of steel, comprising substantially an explosion piston 8 fitting the combustion explosion end or chamber 2 of the cylinder, a cross-head supporting section 9 and a hammer-head or impact member 10.

110 In the embodiment of my invention shown in Fig. 1, the hammer-head 10 comprises a piston 11 rigidly connected to a piston 12 by an integral section 13' of the piston rod 13 integral with which are the explosion piston 8 and the cross-head supporting section 9. The piston 11 is preferably larger in diameter than the piston 12 and it fits and reciprocates in the fuel mixing and transferring chamber 5. The piston 12 similarly fits and reciprocates in the air compression chamber 6 of the fuel intake and compression end 115 120 125 130

or section 4. The piston rod 13 connects the cross-head supporting section with the piston 11 and the cross-head section 9 with the explosion piston 8, in the upper or combustion end 2 of the cylinder 1. The combustion or explosion end or section 2 of the cylinder is provided with a circumferential flange 14 adjacent but spaced upwardly from its lower end, and below said flange, the portion 15 is 5 cylindrical and is made to carefully fit into the cylindrical upper end of the intermediate or rotor supporting section 3 with the bore in the upper section 2 in strict alignment with the axial passage through the intermediate section 3.

The upper end of the explosion section 2 is closed by a cylinder head 16, which is tightly retained in place by studs 17 passing through the flange 14 and threaded into the peripheral flange 18 at the upper end of the intermediate section 3. These bolts or studs 17 are preferably provided with intermediate heads 19 which draw and hold the flange 14 tightly against the flange 18 and the studs 17 are 10 preferably prevented from becoming loose by suitable lock washers 20. Above the intermediate heads 19, the studs 17 pass upwardly through openings through a circular series of thin fins or flanges 21 arranged circumferentially around the upper end of the explosion section 2. These fins 21 provide an extensive surface from which the heat transmitted thereto is dissipated into the surrounding atmosphere. The cylinder head 16 is also 15 preferably provided with a series of similar thin fins 22 disposed radially from the center thereof, for dissipating into the air the heat communicated to the cylinder head from the combustion of the fuel.

Between the fins 22 and in alignment with the studs 17, the cylinder head 16 is provided with sleeve-like spots or lugs 23 formed integrally with the fins 22 and cylinder head and provided with holes through which the 20 upper ends of the studs 17 pass. The upper ends of the said studs 17 are preferably screwthreaded and provided with nuts 24. The center underside of the head 16 is provided with a cylindrical projection 25 fitting 25 tightly into the upper end of the bore in the explosion section 2 and a suitable gasket 26 tightly closes the upper end of the cylinder. The cylinder head 16 is also provided with another spot or boss 27 integral with and connecting two or more of the fins 22 and provided with an opening 28 therethrough, into 30 which is fitted a spark plug 29.

Between the studs 17, the flanges 14 and 18 may be clamped together with shorter studs 30, screwthreaded at their upper ends and provided with nuts 31.

Through the cylinder wall of the top section 2 is a fuel inlet port 32 and substantially aligned therewith on the opposite side of the 35 said cylinder wall is an outlet or exhaust port

or ports 33 disposed as is usual in a two-cycle internal combustion motor. Around the ports 32 and 33, the adjacent fins or flanges 22 are cut away or dispensed with to provide flat seats against which, on the gas inlet side, is 40 fitted a nipple member 34 with a passage therethrough in registration with said inlet ports 32 and screwthreaded to receive the upper end of the fuel transfer pipe 35. The nipple member 34 is held against the flat surface surrounding the inlet ports 32 by a pair of bolts 37, the heads 37' of which lie flat against a flat surface provided around the outlet ports 33, and having nuts 38 on the inlet side for drawing the nipple member 34 tightly 45 against its seat. On the exhaust or outlet side are provided a pair of sheet metal deflectors 36, (see Fig. 24) having a trough or channel 39 on the front thereof adjacent the flat surface around the outlet ports for reception of the heads 37' on the bolts 37. The walls of this channel fit against the sides and 50 top of the head 37' and the said deflectors are held firmly against said flat surface by a screwthreaded extension 37'' on said bolts 55 passing through an opening in the bottom of said channel, and a nut 37''' firmly drawn against the outside of the projection formed by the channel 39 pressed into the members. From a point adjacent the heads 37' of the 60 bolts 37 the deflectors 36 are provided with substantially flat wings converging toward each other to direct the spent or exhaust gases 65 outwardly between the wings and the fins above and blow them away from the hands of the operator, and to keep dust from collecting around and entering the parts 33. Between the nipple member 34 and the seat therefor may be interposed a suitable gasket 70 for securing a tight joint in the gaseous 75 fuel conduit at that point. Lock washers 41 are preferably clamped between the nuts 38 and the nipple 34 to prevent any loosening of the nuts and the parts held together thereby, by reason of the intense vibration to which 80 the tool is subjected while in operation.

The fins 21, 22 are thin and provide a large heat radiating surface and are integral with the metal forming the cylinder walls and the cylinder head. These fins are in continuous 85 metallic engagement with the cylinder and substantially with the piston. Heat is also conveyed or conducted from the cylinder and piston, through the flange 14 directly to the cover 42, lying on and secured to and held in direct metallic engagement with the periphery of the said flange by the bolts or screws 43. Some of the heat of combustion will be 90 also conveyed directly from the lower end of the cylinder 2 into the intermediate section 3 which is also in direct metallic contact therewith. The explosion piston 8 is preferably 95 provided with a plurality of relatively wide piston rings 44 maintained in direct metallic contact with the cylinder walls and the piston 100

so that the heat of the piston may be conducted directly therefrom to the cylinder walls 2 and thence to the parts which are in direct metallic contact therewith. But even with these provisions and expedients, the temperature of the cylinder 2 and piston 8 are relatively high when the drill is in operation, due to the rapid series or succession of explosions in the cylinder 2 to effect the rapid reciprocation of the hammer and the comparatively slow dispersion of the heat. I, therefore, make the combustion or explosion end or section 2 of the cylinder 1 of steel heat-treated in such a way as to make it very strong, tough and hard at the high temperatures to which it is subjected in operating the drill. As a matter of fact, in making the three main members or sections 2, 3, and 4, I preferably used different kinds or grades of chrome nickel steel all differently heat-treated to make each part or section best suited for the conditions of heat and vibration to which it is subjected during the operation of the drill. Thus, the top or explosion section 2 is a drop-forging of Carpenter steel #5-317, chrome nickel steel, heat-treated before machining by heating the forging to a temperature of 1450° F. to 1475° F., quenching it in oil and then drawing it back to a temperature of from 900° F. to 1000° F. This heat treatment is effected before the piece is machined.

The intermediate or rotor supporting section 3 is a drop-forging of Carpenter #3-317 chrome nickel steel, heat-treated after rough machining and after finishing the surfaces of the guide slots 47 for the cross-heads. The faces of these slots are first all carburized or case hardened in a carburizing box at temperatures between 1600° F. and 1650° F. while the rest of the forging is protected by banding or clay packing. The forging is allowed to cool in the carburizing box after which it is heated to a temperature of from 1550° F. to 1575° F., quenched in oil, re-heated to a temperature of from 1350° F. to 1375° F., quenched in oil and drawn at 900° F. The fuel and intake end or section 4 of the cylinder is also a steel drop forging, preferably of Carpenter chrome steel #5-317, but in this case the heat-treatment follows the rough machining of the part and is for toughening the steel, particularly on account of the shocks or vibrations which it is required to absorb. This forging is preferably heated to a temperature of from 1500° F. to 1525° F., quenched in oil and drawn to 1000° F. In this way the steel of each of the three main sections of the cylinder 1 are different in the completed cylinder. Each section is made so as to withstand the peculiar continuous severe vibration to which the drill, as a whole, is subjected; even under the relative higher temperatures to which the explosion end of the cylinder is subjected, the heat of said explosion end being conducted through the metal

throughout the whole cylinder but to varying degrees. When the parts are made in the manner above described, I have found the drill to operate in a highly satisfactory manner.

In the foregoing the steels which are preferably used in the construction of the three parts of the cylinder have been referred to by the terms used in the trade. Carpenter steel of the No. 317 type is a chromium nickel steel containing chromium 1.00% and nickel 1.75% and thus corresponds in alloy content to the S. A. E. Series No. 3200 (Society Automotive Engineers Series). In the Carpenter series the numeral before the hyphen indicates the approximate carbon content, just as in the S. A. E. series the last two numerals indicate the same carbon content. Carpenter steel No. 5-317, chrome nickel steel, contains substantially chromium 1.00%, nickel 1.75%, carbon .50% and corresponds substantially to S. A. E. steel No. 3250. Similarly, Carpenter steel No. 3-317, chrome nickel steel contains chromium 1.00%, nickel 1.75%, carbon .30% and corresponds to S. A. E. standard No. 3230 chrome nickel steel. It is to be understood, however, that I do not wish to be limited strictly to the exact steels above mentioned nor to the exact treatment, the above being given by way of example of one manner in which the invention herein described may be put into practice.

Near the lower end of the upper section 2 and surrounding said section and seated on the underside of the flange 14 and between said flange 14 and the upper ball race 45, is a laminated shim or washer 46 of the proper thickness to insure the fit of the parts.

The intermediate or rotor supporting section 3 is in the main circular in cross-section, but it is provided with a pair of parallel slots or guideways 47-47 diametrically opposite each other and extending parallel to the axis of the cylinder. I preferably provide inwardly directed parallel flanges 48 extending inwardly from the vertical side edges of the slots 47. The lower end 3' of the section 3 is preferably a little larger in diameter both outside and inside than that of the portion containing the slots 47-47, thereby providing two stepped peripheral flanges, 49, 50, respectively, namely, the flange 49, spaced from the lower end, and the flange 50 at the lower end of the section 3. Seated on the upper stepped flange 49 is a ball-race 51; seated on the upper side of the stepped flange 50 and surrounding the section 3 is the oil pan 52; and bolted against the lower face of the flange 50 is the upper peripheral flange 53 of the fuel intake and compression end section 4. A ring or washer 54 also surrounds the lower end 3' of the intermediate section 3 and rests against the upper surface of the bottom of the oil pan 52 and a series of bolts 55 and nuts 56 passing through said washer

54, clamp together the said ring or washer 54, the bottom edge of the pan 52, the flange 50 and the flange 53, and serve to rigidly connect the lower section 4 with the lower end 6 of the intermediate section 3. Preferably, 5 lock nut washers are inserted or interposed between the nuts 56 and the flange 53 to prevent the loosening of the bolts by the vibration of the machine when operated. The upper flange 49 near the lower end of the intermediate section 3, makes the diameter of the opening at the extreme lower end of the said section, larger than it is above said flange. For the purpose of securing exact alinement 10 of the lower section 4 with the intermediate section 3, the upper cylindrical end 57 of the lower section 4 extends into and tightly fits within the axial bore of the intermediate portion 3 above the flange 49, and an annular flange 58 on the upper side of the flange 53 fits within the larger part of the said bore below the flange 49. Thus the fuel intake and compression section 4 is also provided with a cylinder 60, preferably of smaller bore 15 and which, with the hammer-head 10 and the closure 61 for the lower end of the said cylinder, forms the air compression chamber 6. The closure for the lower end of the cylinder 60 is the anvil 61 in which is slidingly mounted the strike-pin 62 provided with a small axial bore 63 therethrough and at its lower end with a head 64 squarely fitting against a shoulder 65 formed by the counter-bore 66 at the lower end of the bore 63. The head 20 59 of the anvil 61 rests squarely against the lower end of the cylinder 60. The cylindrical surface of the anvil 61 is provided with a plurality of circumferential channels 67 which, during the operation of the machine 25 are maintained filled with oil, thereby making an airtight seal between the interior of the chamber 6 and the exterior of the anvil 61. The chuck 68 is provided with a plurality of coiled springs 69 (one only is shown) 30 bearing against the upper surface of the flange 70 at the lower end of the cylinder 60 and compressed between said flange and a nut 71 on the upper end of a bolt 72 passing through said flange 70 and through arms 73 35 extending radially from the top edge of the chuck 68.

The cross-head supporting section 9 of the piston-hammer 7 is substantially rectangular in transverse cross-section with the corners 40 74 between the straight sides rounded or arcuate. It is provided with a cylindrical bore 75 extending straight through it at right angles to the axis and piston; with a keyway 76; and with a transverse tapering hole 77, circular in cross-section, the axis of which is preferably tangential to the bore 75 and this hole 77 is preferably disposed in a plane at right angles to the axis of the hole 75 and passes through the axis of the piston-hammer 7. 45

50 This tapering hole 77 (see Fig. 20) is pref-

erably drilled or formed after the cross-head pin or stud 78 has been positioned in the cross-head supporting section 9 and will be referred to again below. The cross-head pin or stud 78 comprises a middle or central portion 79 of uniform diameter and of a length equal to the length of the bore 75 through the cross-head supporting section 9. On each side of this middle portion 79, the cross-head pin is provided with a cylindrical section 80—80 of slightly reduced diameter forming journals upon which are mounted to rotate steel rollers 81—81 respectively of preferably a diameter equal to the width of the flanges 48 along the opposite vertical edges of the slots or guideways 47—47 through the walls of the rotor supporting section 3 of the cylinder 1. At the outer ends of these journals 80—80, the cross-head pin or stud 78 is again slightly reduced in diameter to form journals 82—82 for steel rollers 83—83 respectively and outside of these rollers are cylindrical rings 85—85 rigidly secured to the ends of the cross-head pin 78 by tapered pins 86—86 tightly drawn into correspondingly tapered holes through said rings 85—85 and through the ends 82—82 of the cross-head pin or stud 78. The middle or central portion 79 of the cross-head pin 78 is provided with a key 87 which fits into the keyway 76. The fit of the intermediate portion 79 of the pin within the bore or hole 75 is a tight driving fit, the key 87 fitted into the keyway 76 being operative to prevent the pin 78 from turning on its axis while it is being drawn into the hole 75 or after it is in position therein. When properly positioned in the cross-head supporting section 9 with the ends of the intermediate portion 79 flush with the outer surfaces of said portion, the tapered hole 77 is drilled or formed through the cross-head supporting section 9 and through the outer surface of the cross-head pin or stud 78 and after the tapered hole is so formed, a tapering pin 88 is driven tight into said hole. Thus, the key 87 and keyway 76, together with the frictional engagement between the cross-head pin and the cross-head supporting section 9 prevent any rotational movement of the pin within the cross-head section 9, and the tapering pin 88 cutting through the surface of the cross-head pin 78 prevents any longitudinal movement of the cross-head pin and the parts are rigidly secured together in such a way that they will not work loose notwithstanding the severe vibration to which the drill is subjected during the operation thereof. The rollers 81—81 are substantially anti-friction rollers and serve to reduce the wear between the cross-head pin and the guide slots 47—47, the walls of which are case hardened. The rollers 83—83 cooperate with a cam path 89 formed between the upper part 90 and the lower part 91 of the cam cylinder 92. 100

105 The hub or rotating member 93 upon which 110

130

the cam cylinder is mounted, is also made preferably of two parts, the upper part 94 being secured to the lower part 95 by a series of studs 96 rigidly secured to a flange 98 on the lower part 95 and passing through a cooperating flange 97 on the upper part 94 and held thereto by nuts 99 provided with lock nut washers 100. To the inner cylindrical surface of the lower part 95 of the hub member 93, the lower part 91 of the cam 92 is fitted and secured rigidly in place by rivets 101-101. The lower edge of the lower part 91 of the cam 92 is seated against a square shoulder 102 in the hub portion 95. In the same way the upper portion 90 of the cam cylinder 92 is fitted within and is rigidly secured to the inside of the upper part 94 of the hub or rotating member 93 being provided with a shoulder 103 bearing against the inner edge of the opening through an inwardly extending flange 104 near the upper end of the upper portion 94 of the hub or rotating member 93.

While I have referred to the space between the adjacent edges of the upper part 90 and the lower part 91 of the cam cylinder as a cam path 89, it is to be understood that this space is preferably of uneven width so that said adjacent edges form substantially two more or less independent cam surfaces 105-106 respectively. The cam surface 106 on the lower part 91 is preferably the only surface which is in substantial engagement with the cam rollers 83 when the device is operating by the explosive action of a gaseous mixture in the explosion end or section 2 of the cylinder 1. The cam surface 105 of the upper portion 90 of the cam cylinder is in the main for the purpose of cooperating with the said rollers 83 in starting the motor by manually rotating the flywheel and so forcing the piston-hammer 7 downwardly to effect an intake of gaseous mixture in the explosion end of the cylinder. Both cam surfaces 105 and 106 are respectively duplex in character, that is to say, each cam surface is repeated on diametrically opposite points of the axis of the cams and given exactly the same contour or outline so that during a complete rotation of the cam, the cam follower rollers 83-83 and consequently the piston-hammer cooperating therewith will make two complete reciprocations for every revolution of the cam. The inner surface of the lower part 95 of the hub 93 is provided with a thickened portion 95', (see Fig. 12), the upper edge of which parallels generally but is spaced a little below the cam surface 106 of the cam 91. To this thickened portion 95' the lower part 91 of the cam cylinder 92 is secured by the rivets 101. Similarly, the inner portion of the upper part 94 of the hub 93 is provided with a thickened portion 94' and the lower edge thereof generally parallels but is spaced slightly above the cam surface 105 of the cam

90 and to this thickened portion, the part 90 of the cam cylinder is similarly secured by rivets or screws 107 in holes 107', as indicated in Figs. 10 and 11. The characteristic features of the cam surfaces 105 and 106 will be referred to again below. 70

Above the flange 104 in the upper part 94 of the hub 93 is a square seat or shoulder 108 (see Fig. 11) in which is seated a ball race 109, and a series of anti-friction balls 110 are suitably interposed between the ball races 45 and 109 respectively. It is preferably upon this upper part or half 94 of the hub 93 that the balance or momentum wheel 111 is carried, preferably integrally with the hub portion 94. The lower end of the lower part 95 of the hub is preferably recessed annularly to provide a square shoulder or seat 112 for a ball race 113 forming a part of an anti-friction bearing which also includes the anti-friction balls 114 and the ball race 51 seated on the upper stepped flange 49 at the lower end of the intermediate rotor supporting section 3. Thus it is that the cam cylinder 92 as a whole, the hub 93 as a whole and the balance or momentum wheel 111 and the parts carried thereby constitute the rotor 116 of the mechanism by which the rectilinear reciprocatory motion of the piston-hammer 7 produces a rotary movement 90 of the rotor 116. The energy thus stored in the rotor is used to effect the return or compression stroke of the piston-hammer, as well as to control and operate the timing mechanism 117 of the ignition system of the motor. 95

Above the rotor 116 and rigidly secured to the upper side of the flange 14 of the combustion section 2 is an annular cover 42, the lower edge of which generally extends downwardly and lies close to the upper surface of the rim of the balance or momentum wheel 111 but said cover 42 is provided with a pair of diametrically oppositely disposed recesses 120-120 provided with strengthening lugs 121 in the inner walls thereof, providing vertical flat faces 121'-121' upon which are secured the inner ends 122' of handles 122-122 by suitable bolts 123, 123'. 100

The cover 42 is also preferably provided with a seat or pocket 124 cast integrally therein of a size and shape to seat and hold an ignition unit 125 comprising a suitable induction coil 322-326 and condenser 328 for the ignition system of the mechanism and referred to again below. This ignition unit 125 when placed in the seat or pocket 124 in the cover 42 is not far from the outer end of the spark plug 29 so that a single short insulated electric conductor 126 may be employed to connect the coil with the spark plug. When so disposed, the conductor 126 may be rigidly secured to the binding posts 127 and 128 of the spark plug and electric unit respectively and that short connection will not be subject to twists or excessive vibration and conse- 115 120 125 130

quent frequent rupture while the drill is in operation. The conductor 126 is out of the way. It is not liable to be caught on objects close to which the drill may be brought, or with the hands, or arms of the operator, for it is out of the way, fairly well protected by the framework by which the drill is guided, held and carried from place to place as will be referred to again below. The likelihood 10 of breaking the electric circuit by breaking the conductor 126 or detaching it from the binding posts 127 and 128 is greatly minimized.

The cover 42 is provided with a recess 129, 15 constituting an interruption in the continuity of the periphery of the cover. In this space or opening or recess 129 is mounted a contact maker or timing mechanism 117 which will be referred to again below. This contact 20 maker 117 is preferably rigidly secured to the vertical wall 131 of the recess 129 directly over the balance wheel 111. On the upper surface of the balance wheel, in such a position as to pass directly under the contact 25 device 117, are two relatively small steel plates 132, diametrically disposed with respect to the axis of the balance wheel (only one is shown in Fig. 1) and rigidly secured thereto by a bolt 119 and a steady pin 130. Each plate 132 is provided with a narrow 30 substantially radially extending tapering projection 133 so that as the plates successively pass under the contact maker 117 the projections 133 will engage a vertically slid- 35 able rod or plunger 134 in the contact maker 117 and lift the same to bring a movable contact point of the lower portion 135 of the contact maker 117 into engagement with a stationary contact point of the upper portion 40 of the contact maker 117 which is in electrical communication with a binding post 137 but which is insulated from the cover 42. Because the binding post 137 is in the primary circuit of the ignition system of the tool, 45 the primary circuit will thus be intermittently closed by the contact maker 117. Preferably this contact maker 117 is enclosed by a small metallic cover 138 which fits over and closes the recess or space 129 in the an- 50 nular cover 42.

The oil pan or casing 52 is preferably substantially circular in horizontal cross-section. In vertical cross-section it slowly curves from the edge of the circular opening through the 55 bottom thereof upwardly and outwardly to a point near the top thereof and its upper edge 139 is then curved inwardly and downwardly close to the outer circumferential surface of the hub 93. The flange 98 at the top 60 of the lower portion 95 of the hub 93 is preferably provided with an annular recess 140 into which projects but without contacting with the walls of said recess, an annular ring 141 projecting vertically upwardly from 65 substantially the highest portion of the wall

of the pan 52. Within the pan 52 and near the bottom thereof is an inwardly extending continuous annular flange or ridge 142 forming a shallow oil retaining chamber 143 into which project the lower ends of preferably two inclined oil conducting tubes 144, preferably diametrically oppositely disposed with respect to the axis of the rotor and passing upwardly through the thickened portions 95, 95' of the lower part 95 of the hub 93. The lower ends of the tubes 144 are in advance of the upper ends and when the rotor is rotating rapidly and the lower ends of the tubes 144 dip into the oil, the inertia of the oil will cause the tubes to scoop up the oil and the oil will substantially flow upwardly through the tubes and be discharged as a stream against the rollers 83 on the cross-head pin 78 and the cam edges 105 and 106, thus insuring a thorough lubrication of the cam surfaces 105 and 106, the rollers 83, 83 coating therewith, the guideways or slots 47 and the rollers 81, 81 cooperating therewith. If for any reason the supply of oil in the pan 52 be allowed to be depleted and the drill is being used in a 90 tilted position, that is, at an angle to a vertical or perpendicular position, then the inwardly extending low annular ridge or rib 142 will retain a substantial quantity of oil in the pan in a position where the ends of the 95 tubes 144 will still dip into it on every revolution of the rotor and the likelihood of affording insufficient lubrication for the cams, cross-head and guideways is greatly reduced.

The upper inturned edge 139 of the pan is 100 for the purposes of preventing oil from being spilled out of the pan when the drill is held or supported at a decided angle to the perpendicular and the similar inturned ridge or rib 142 insures the retention of sufficient oil 105 at the bottom of the pan whence it may be lifted by the rapidly revolving inclined tubes 144 when the tool is being used in such a position that were it not for the ridge or rib 142, all of the oil would flow to a place where the 110 lower edges of the tubes 144 would not dip into it and lift it.

Extending outwardly from the side of the pan is a snout or tubular inlet 145, preferably normally closed by a cap 146 and gasket 147, 115 the cap being retained in place by a resilient bail 148, the ends of which are pivotally connected to the sides of the snout and the loop of which fits and locks or snaps into a recess or groove 149 in the top of the cap, when the cap is in closed position. It is through this snout or inlet 145 that oil may be introduced for the lubrication of the operative parts of the drill.

The chuck 68 is preferably in the form of 125 a sleeve 150 having an axial hole 151 therethrough of any suitable shape in transverse cross-section, such as a square hole or a hexagonal hole to fit on, over and around the end of a tool insertible therein and correspond- 130

ingly shaped. The outside of the sleeve is preferably provided with two flat parallel faces or surfaces 150' (see Fig. 15). Around the sleeve 150 and bearing against the shoulder 152 on the sleeve 150 adjacent the flange 73 is a ring or washer 153, preferably provided with a downturned circular flange 154. The hole 153' (see Fig. 16) through this washer is substantially of the size and shape of the exterior of the sleeve 150. Within the flange 154 of this washer 153 is fitted the upper end of a coiled spring 155 surrounding the sleeve 150 and having its opposite end normally pressing against a collar or retainer 156 having a circular recess 159 in its lower face and fitting over and around a split ring 157. The passage 156' through the collar 156 is of the same size and shape as that of the outside of the sleeve 150. This split washer 157 is circular and preferably L-shaped in cross-section and its outer diameter fits into the cylindrical recess 159 in the lower side of the collar or retainer 156 and its inner diameter fits a circular channel 158 of the sleeve 150 near the lower end of the sleeve 150 and of a diameter slightly less than the distance between the parallel faces 150'-150'. The L-shaped split ring 157 is seated in the groove 158 and is held there by the walls of the recess 159 in the lower ring, washer, collar or retainer 156. In this manner the parts of the chuck 68 are held together in their operative positions and relationship. On opposite sides of the ring or washer 153 pins or lugs 161 project in diametrically opposite directions and they are encircled by eyes 162 on the end of a drill or tool retainer 163 which is thus pivotally mounted on said pins or lugs 161. The collar or retaining member 156 is widened on its rear side adjacent the operator and is provided with a pair of substantially semicircular recesses 160 into which the parallel lengths of the tool retainer 163 snap and by which they are retained in place to hold the drill in the chuck 68, as is clearly indicated in Fig. 17.

For holding and steadyng the machine in operation, I have provided a framework made of two tubular rods 164 connected together and bent into convenient form and shape. These two somewhat complementally arranged rods 164, preferably consist of vertically-extending tubular portions 165, at the upper ends of which are substantially horizontally extending portions 166 terminating in eyes 167 through which pass the longer bolts 123' which hold the handles 122 on the annular cover 118. The vertically extending sections 165 are preferably provided with aligned complementally arranged inwardly directed lugs 168, 168 and are connected together by a hollow cross-bar 169, the ends of which are welded to the vertical portion 165. Below the vertical portions 165 the said bars 65 are provided with inwardly extending con-

verging portions 170 terminating in eyes 171 adapted to fit against the opposite sides of a lug 118 extending rearwardly from the lower end of the fuel and intake section 4 and are securely held in place by a bolt and nut 172 extending through the said lug 118 and through the eyes 171.

Between the two main vertical portions 165 and pivotally mounted upon the cross-bar 169 is a knee-plate 173 which is preferably made of sheet metal and the lower portion 173' thereof is preferably vertically concave, to substantially fit against the thigh or leg of the operator. This knee-plate 173 is pivotally mounted on the cross-bar 169 by straps or brackets 174 substantially encircling the cross-bar 169 and secured to the knee-plate by bolts 175. The inwardly directed lugs or projections 168 are engaged by the sides of a portion of the knee-plate 173 above the cross-bar 169, when it is in its substantially vertical position and are operative to prevent further rotative movement of the knee-plate in an anti-clockwise direction. These lugs 168 serve as stops to prevent the movement of the upper part of the knee-plate inwardly toward the cylinder after it engages with the lugs 168. By means of the handles 122 and the framework partly supporting the tool on the thigh by the knee-plate 163 an operator may with facility carry, hold, direct, steady and guide the tool in using the same.

Secured to the horizontal upper portions 166 of the framework are a pair of brackets 176. These are preferably made rigid with the frame by spot welding and upon these brackets is mounted and supported a tank or fuel reservoir 177 of light steel sheet metal construction and provided with lugs 178-178 which rest upon the brackets 176 and are secured thereto by bolts 179-179. The tank 177 is preferably provided with a snout or a filling tube 180, the upper end of which is arranged to be closed by a suitable cap 181 and resilient bail 182. Between the cap 181 and the end of the snout 180 is preferably interposed a gasket 183 (see Fig. 13). The cap, bail and gasket are preferably identical with those used to close the snout on the oil pan 52.

The bottom of the tank 177 is provided with a projection 177' to which is secured a nipple 184 over which is threaded a coupling 185 at the upper end of the gasoline feed pipe 186, the lower end of which is connected by a coupling 187 to the upturned end of an elbow bracket or nipple 188. This elbow bracket or nipple 188 is provided at its opposite end (see Fig. 6) with a suitable flange 189 adapted to be fitted tightly against a cooperating flange 190 on one end of the body 191 of the carburetor 192. The two flanges 189 and 190 are clamped together by bolts 193 with a gasket 194 clamped between said flanges.

The carburetor 192 is composed in the main of two parts, namely, the carburetor body 191 and the carburetor cap 195. The carburetor body 191 is the part to which the gasoline supply pipe 186 is attached and it is provided with a longitudinally cylindrical hole 196 into which is threaded the needle valve stem 197. The inner end of this hole 196 is provided with a shoulder 198 forming a seat for the pointed conical end 199 constituting the needle valve and beyond this shoulder 198 is a hole 200 of small diameter communicating at its other end with a counter-bore forming a chamber 201 which is in alinement with and communicates with the lower end of the elbow bracket 188 through the gasket 194. At the right hand end of the carburetor body 191 there is formed a screwthreaded recess 202 into which is threaded the packing gland 203 serving to compress the packing 204 around and against the needle valve stem 197 to prevent leakage of gasoline around that end of the carburetor body. The outer end 205 of the needle valve stem is provided with an arm or lever 206 rigidly secured thereto and serving as a handle by means of which the stem of the needle valve may be rotated to move the conical end 199 toward and away from its seat on the square shoulder 198. The end of the arm 206 is preferably provided with a plunger 207 which is preferably pressed by a spring 208 toward the carburetor and to hold the V-shaped or chisel-shaped end 209 thereof into engagement with any one of a series of notches 210 arranged in an arcuate projection 210 on the right hand side of the carburetor cap 195 (see Figs. 6 and 14). As the arm 206 is manually swung to any desired position, the chisel-shaped end 209 rides over the ridges formed by the notches or serrations 210 and when the valve 109 has been so properly adjusted the plunger member 209 is held in the coacting notch by the spring 208, thus holding the valve in its adjusted position whence it will not be moved by the vibration of the machine when operating. Communicating with the hole or chamber 196 and disposed at right angles thereto is a small duct or passage 211 which turns abruptly vertically and then extends laterally at an angle into and through the wall of the tapered valve seat 212 (see Fig. 6) on which is seated a valve 213 preferably provided with an axial cylindrical stem 214 extending downwardly through a bearing 215 in which said stem 214 is longitudinally slideable. This bearing 215 is preferably formed in a bar or strut 216 which extends diametrically across the opening 217 directly beneath the valve seat 212 and communicating with the atmosphere. Around this valve seat 212 and concentric therewith is a cylindrical wall or projection 218 over and around which is fitted the car-

buretor cap 195, the latter being secured to the body 193 by bolts 219 and nuts 219' as shown in Fig. 5. The carburetor body 191 is provided with a flat face 220 adapted to fit squarely against a flat face 221 of a projection 222 on the wall of the cylinder and through which is a passage 223 communicating with the fuel mixing and transfer chamber 5. There is preferably a gasket 224 interposed between the two flat faces 220 and 221. The bolts or studs 225 are provided with a shoulder or enlargement 226 drawn tight against the flat face 221 by the screwthreads 225' on the end of the stud 225 and in the projection 222 on the cylinder wall. The holes 228 through the carburetor cap 195 are provided with a counter-bore 227 at one end for the reception of the enlargements 226, and a counter-bore 229 at the other end for the reception of nuts 230, by means of which the carburetor cap 195, and the parts secured thereto are rigidly mounted on the cylinder with the gasket 224 compressed between them. The outer ends of the bolts or studs 225, pass through the flange 234 of the elbow 235 and are provided with screwthreads 231 over which are tressed nuts 237 with lock washers 237' for holding the elbow 235 of the fuel transfer pipe 35 with its flat face 243 against the flat face 233 of the carburetor with the gasket 236 compressed between them. In this way the fuel transfer pipe 35 is put into direct communication with the passage or chamber 222 through the carburetor cap 195 over the valve 213. On the upper side of the valve 213 is preferably arranged an axial projection 238 around which is seated a coiled spring 239, the upper end of which also preferably surrounds a projection 240 formed on the upper wall of the chamber 232. The function of the light spring 239 is to normally hold the valve 213 on its tapered seat 212. Extending through the upper wall of the cap 195 and preferably in axial alinement with the valve 213 and its seat, is an adjusting screw 241, preferably provided with a lock nut 242. The lower end of this screw 241 is normally adjusted to a position slightly above the top of the projection 236 on the valve 213 and serves to limit the vertical movement of the valve when lifted off its seat. The cubical capacity of fuel mixing and transfer chamber 5 is determined by the diameter of a split cylindrical sleeve 244 extending the full distance between the pistons 11 and 12 of the hammer-head clamped around the piston-rod section 13'. The two halves of the split sleeve 244 are held together around the rod 13' by bolts 245 passing transversely therethrough (see Fig. 21). The space between the outer surface of the sleeve 244 and the inner walls of the fuel mixing or transfer chamber 5 at the end of 130

the upward stroke of the piston-hammer constitutes the capacity of the chamber. If the capacity of the chamber be found to be insufficient, a smaller sleeve 244 will be similarly clamped to the piston-rod section 13'. 5 If the amount of air taken in the said chamber 5 be too great, then a larger sleeve will be similarly secured to the piston-rod 13'. In this way the amount of air taken into the chamber 5 may be determined and made to 10 be exactly right and unvariable for the explosive mixture. It is to be understood, of course, that the diameter of the chamber 5 is such that a sleeve 244, of greater diameter than the hammer-head 10 will never be 15 needed.

In the form of my invention illustrated in Fig. 1, the lower end of the hammer-head 10 is the piston 11 which fits into the chamber or cylinder 6 forming the air compression chamber. To admit air into this chamber, the wall thereof is pierced by a port 246 which passes through the wall of the cylinder and through a lug or projection 247 extending outwardly from the outer wall of the cylinder and provided with a square face 248 against which is adapted to be rigidly secured the flat face 249 of the pop-valve or pressure regulating valve 250 with a gasket 251 between them. In Figs. 7, 8 and 9, this pop-valve 250 is shown as secured tightly up against the flat space 248 of the projection 247 by screws or studs 252 rigidly screwed into the projection 247 and passing through 25 holes 253 through the casting of the pop-valve 250, (see Fig. 7) and as provided at their free ends with lock nuts 254, and with lock washers 254' preferably interposed between the nuts 254 and the valve body. This 30 pop-valve 250 comprises a casting provided with a relatively large cylindrical chamber 255, the upper part of which communicates directly with the air port 246 by a passage 256. Within this cylindrical chamber 255 is fitted a cylindrical sleeve 257 having in its upper or inner end a tapered valve seat 258 and having at its lower end a flange 259 secured to and held against the flange 260 at the lower end of the casting by one or more bolts 261 with nuts 261'. Seated on this valve seat 258 is a valve 262 from the lower side of which preferably extend a circular series of fins or guides 263 slidably fitting against the cylindrical passage 264 through the sleeve 257. 40 A cylindrical projection 265 is preferably provided on the upper side of the valve 262 around which is fitted the lower end of a coiled spring 266, the upper end of which presses against the upper wall of the chamber 255 above the valve. I preferably also secure to the bottom of the cylindrical sleeve 259, a deflector 267 of preferably sheet material, preferably inclined downwardly and inwardly toward the axis of the cylinder and 45 terminating in a horizontally disposed up-

wardly inclined bell or mouth 268 so that the dust blown upwardly from the hole being drilled will not be drawn directly into the pop-valve on every upward reciprocation of the piston 11; and so that the heavier particles of dust will be prevented from entering the pop-valve. 70

Through a passage 269, the chamber 255 communicates with one end of a cylindrical chamber 270 in which there is a piston 271 mounted on a piston-rod 272 which passes through a head or cap 273 closing the chamber 270 and the outer end of this rod 272 is provided with a winged member 274 somewhat resembling a winged nut but rigidly secured to the outer end of the piston-rod 272 as by a pin 275. The head or cap 273 is secured to the casting (to close the cylindrical chamber 270) by screws 276. Between the piston 271 and the head 273 and surrounding the rod 272, is a coiled spring 277, under compression, tending to force it toward the opening or passage 278 and to hold a valve 279 on the end of the piston-rod 272 against its seat 280. This valve 279 when on its seat 90 280 closes the passage 278 leading from the cylindrical chamber 262. The outer surface of the head 273 is provided with a circular annular projection 281 preferably concentric with the axis of the piston-rod 272 but the outer end of which is provided with complementally diametrically disposed inclined edges 282, the inclination, however, being comparatively slight. These inclined edges 282 substantially form slowly rising cam surfaces and they are preferably provided with diametrically disposed grooves or notches 283 into which fit the adjacent edges 284 of the wings 285 of the winged member 274. When the winged member 274 is rotated slowly over 100 the inclined edges or cams, the inner edges 284 of the wings will be forced out of one pair of diametrically oppositely arranged grooves 283 into the next pair of grooves and when the said member is rotated in a clockwise direction, reference being had to Fig. 6, then the succeeding grooves will be more and more remote from the flange of the cylinder head or cap 273 and this upward movement will 110 slightly lift the valve 279 from its seat 280. In this way, the position of the valve 279 with respect to its seat 280 may be quite delicately adjusted. The function and operation of this pop-valve will be described below. 115

While I may employ any suitable timing mechanism for the ignition circuit, I have found the mechanism herein shown and particularly in Fig. 4, to be well adapted for the purpose. The stationary contact point 136 consists of a holder 286 provided with a threaded hole 287 therethrough into which is fitted the stationary contact screw 288 provide at its lower end with a tungsten tip 289. The holder 286 is provided with a flange or bracket portion 290 adapted to be seated 120 125 130

and held upon the vertical wall 131 by the bolt and binding post 137. The bracket or flange 290 is, however, insulated from the cover 42 by a sheet or plate of insulating material 291 between the holder 286 and the wall 131, and the bolt 137 which passes through the wall 131 of the cover is also insulated therefrom by suitable insulating bushings 292 between them and the cover 42. The nut 137' secures the bracket 286 stationary with respect to the cover 42 and the inner end of the bolt 137 is provided with a nut 293, thus making of the bolt a binding post for the connection thereof with the electrical system of the device. Below this stationary contact member 136 is the movable contact maker 135 which consists of a metallic housing 294 securely fastened to the lower part of the wall 131 by bolts 295 passing therethrough and threaded into the metal of the cover 42. Within this housing 294 is a timer plunger shell 296 also of metal and having a vertical passage therethrough providing a shoulder 297 near the lower end thereof. This shell 296 is also provided with an axial passage therethrough of two diameters, the lower portion of the said hole being of the smaller diameter to provide a shoulder 298 therein upon which is normally seated the annular flange 299 of the timer plunger 300. The upper end of the passage or bore through the timer plunger shell 296 is preferably counter-bored somewhat to provide an annular shoulder 301 near the top end of the shell for the reception of a washer 302 and the disk-like flange 303 of the timer plunger bearing 304. The upper end 305 of the timer plunger shell 296 is preferably made thin so that after the parts are assembled in the shell the said upper edge 305 may be spun over inwardly against the upper surface of the flange 303 to retain the timer plunger bearing 304 fixedly in position within the shell. Between the upper surface of the flange 299 of the timer plunger 300 and the washer 302 is a coiled compression spring 306 tending to normally hold the flange 299 on its shoulder or seat 298 and the lower end of the plunger on or close to the plane surface of the plates or rings 132 and in the path of the projections or knife edges 133.

Just above the plane of the surface of the upper ends of the timer housing 294 and below the thin upper edges 305 of the shell 296 is provided a shoulder 307 upon which is seated a plate or washer 308 through which the upper end of the shell 296 passes, said plate being secured to the upper surface of the housing 294 by suitable screws 309. The purpose of this plate and screws is, of course, to permanently hold the shell 296 within the housing 294. In Fig. 1 I have shown the timer or contact maker 117 and the ignition unit 125 as being diametrically oppositely disposed on the cover and in the plane passing through the axis 65 of the cylinder and midway between the ver-

tical portions 165 of the frame work, but these parts are so shown in Fig. 1 for the sake of combining as much as possible in a single figure. But I prefer to provide the seats or recesses to receive both the contact maker and the electrical unit on the rear side of the machine adjacent the operator in the manner shown in Fig. 3 for in this way the timer and electrical unit are brought close to each other and to the spark plug 29, to provide short connections 126 and 324 between the electrical unit and the binding posts 127 and 137 respectively.

In Fig. 10 is shown the cam cylinder 92 comprising the upper portion 90 and the lower portion 91. The lower portion 91 provided with a cam surface 106 is substantially the only cam surface which is operative during the normal operation of the drill after it has once been started. It will be plain that with such cams as have been above shown therein, there will necessarily be two complete reciprocations of the piston-hammer for every revolution of the rotor. From the high point 310 of the cam portion 91, the cam path 106 is provided with a steeply inclined portion 311 which extends for a little more than one-half the stroke of the piston-hammer and this inclined portion 311 terminates in an abrupt drop 312 during which the roller 83, cooperating therewith, is out of engagement with the cam 91 up to the end of the stroke. From the lower end of the abrupt drop portion 312, the portion 313 is a slowly rising surface up to the next high point 310 of the cam 91 and on the opposite side of the cam cylinder, after reaching which the cam surfaces 311, 312, 313 repeat back to high point 310 first above mentioned. During all this time, the upper portion 90 of the cam cylinder is preferably out of contact with the roller 83.

But the cam surface 105 of the portion 90 is preferably provided with a sharply descending portion 314 extending practically parallel to the steeply inclined portion 311 of the other cam 91 and down to a low point 315 which is so positioned that in starting the device the operator, by manually rotating the rotor 116 in the direction indicated by the arrow 316 will force the roller 83, contacting therewith, downwardly and with it the cross-head 78 sufficiently to uncover the ports 32 to permit the explosive charge to be supplied to the explosive end of the explosion cylinder. Beyond the low point 315, the portion 317 of the cam surface 106 rises sharply and then approaches the slowly rising portion 313 of the cam 91 so that the point 318 over the high point 310, is separated from the high point 310 by a distance slightly greater than the diameter of the roller 83.

The lower cam portion 91 is shown as provided with holes 101 for the reception of the bolts or rivets 101 by means of which it is

secured to the lower part 95 of the hub 93 and similarly, the upper portion 90 of the cam is provided with holes 107 for the reception of similar bolts or rivets 107 for rigidly securing the cam to the upper part 94 of the hub 93.

The electrical unit 125 preferably consists of an induction coil, including a primary coil and a secondary coil and also includes in the structure a condenser.

In Fig. 4 I have shown diagrammatically the electrical unit 125 and the electrical connections therefrom and thereto. The source of electricity is usually a battery 319 (either dry cells or a storage battery), which may be placed upon the ground and from which run two wires 320 and 321 to the electrical unit 125. The wire 320 is preferably grounded to the machine in any suitable manner and as indicated in the diagram, and the other wire 321 is preferably connected to one end of a primary winding 322 within the unit 125. The other end of the primary winding 322 is electrically connected with the binding post 323 on the outside of the unit 125. An insulated wire 324 which is short and so disposed as to be not liable to be caught on objects during the handling of the machine, connects the binding post 323 on the unit with the binding post 137 of the stationary contact 136. Since none of the parts of the movable contact member 135 are insulated from the annular cover 42, it is grounded to the machine as indicated by the connection 325 and ground in Fig. 4 of the drawings. The wire 321 may also be connected to one end of the secondary winding 326 which is within the unit 125 and the opposite end of the said secondary winding 326 terminates in the binding post 128 which is connected by the conductor 126 with the spark plug 29, one side of which is grounded to the machine, as indicated by the wire 327. Within the electrical unit 125 is also provided a condenser 328, one side of which is connected by wire 329 to the electrical connection between the primary winding 322 and the contact maker or timer mechanism 117 preferably between the winding 313 and the binding post 323. The other side is grounded to the machine, in any suitable manner, as indicated by the wire 330 and ground. In this way the condenser 328 bridges the gap between the contacts of the contact maker 117.

As the machine in operation is subject to great shock and vibration, those parts which must be adjusted to secure the proper operation of the mechanism, are arranged to be held fixed during the operation of the machine. The turning of the arm or lever 206 on the end 205 of the needle valve stem, is prevented by the spring pressed plunger 207 in engagement with the notches 210', and the stem 197 is prevented from turning within the lever 206 by providing the end 205 of the needle valve stem with one or more teeth 331

and the hole 206' through the lever 206 with intermeshing teeth, both sets of teeth running parallel to the axis of the needle valve stem 197. The end of the lever 206 around the shaft 205 is provided with a kerf or cut 332 extending through to the hole 206' and a clamping bolt 333 is passed through the ears or lips 334 and 334' on each side of the cut or kerf 332. The bolt is preferably threaded into the ear or lip 334 and is held in place by a lock nut 335 after the ears have been drawn toward each other to sufficiently clamp the arm to the end of the needle valve stem.

The bolts 72 which hold the tool chuck 68 to the end of the drill are similarly provided with means to prevent the rotation of the bolts or nuts carried thereby or the springs due to the vibration of the machine. To this end, the undersides of the heads 72' of the bolt 72 are preferably provided with radially extending grooves 336, (see Fig. 1) V-shaped in transverse cross-section, one on each side of the shank of each bolt and the underside of the flange 73 of the chuck on each side of the holes through which the said bolts pass is preferably provided with ridges 337, (see Fig. 15) also V-shaped in cross-section, to fit into the grooves 336. On the upper side of the flange 70 at the lower end of the cylinder and on opposite sides of the holes through which the bolts 72 pass, there are similarly provided radially extending V-shaped grooves 338 extending diametrically from the axes of the holes through which the bolts pass. The underside of the nuts 71 on the upper ends of the bolts 72 are also similarly provided with similar grooves 339. Between the upper surface of the flange 70 and the under surface of the nuts 71, the springs 69 are compressed. The said springs 69 are provided with radially disposed knife-edged projections 340 and 341, (see Figs. 22 and 23) on the lower ends and the upper ends of the springs respectively to engage and fit into the grooves 338 on the flange 70 and the grooves 339 on the nuts 71. It will be seen now that when the springs 69 have been compressed to the desired extent between the flange 70 and the nuts 71, and with the knife-edges 337 in the grooves 336 and the knife-edge 340 in the groove 338, the nuts 71 may be turned to bring the notches 339 into registration with the upper knife-edge 341 on the spring and when so adjusted the parts will remain in that adjusted position free from liability of disengagement or rotation due to the vibration of the machine.

Because of the vibration of the machine, under operation, and the direction of the severe strains imposed upon the mechanism while operating all the essential bolts and studs used to secure together the parts of the cylinder, the cylinder head and the chuck, extend in a direction parallel to the axis of the cylinder, so that there are no shearing

stresses or strains imposed upon said bolts, but only longitudinal strains and stresses thus obviating any breakage of said bolts due to shearing stresses.

5 The studs or bolts 17 for retaining the cylinder head 16 on the upper end of the cylinder 1 and for bolting the explosion section 2 to the intermediate section 3 are parallel to the axis of the cylinder; as are also the bolts 31, by which the sections 2 and 3 are bolted together; the bolts 55 for clamping the flanges of the sections 3, 4 together, and the bolts 72 of the chuck. The strains imposed on these parts are forces tending to elongate, 10 not to shear the bolts and, therefore, withstand the bolts the shock and vibration of the 15 drill for a long time.

Having thus described the general construction and arrangement of the parts of the 20 drill shown substantially in Figs. 1 to 24 inclusive, I will now describe, briefly, the operation thereof. Assuming the parts to be in the position shown in Fig. 1, with the piston-hammer 7 in its upper position and assuming a tool 342 to be retained in the tool chuck 68 at the lower end of the tool, the operator holding the machine in a substantially vertical position with the tool at the point at which the drilled hole is to be made, will 25 grasp with one hand the rim of the fly or balance wheel 111 and whirl it in a clockwise direction, looking down on the drill. This rotation of the flywheel 111 will bring the cam surface 314 of the upper cam cylinder 90 (see Fig. 10) against the roller 83 and will force said roller and the crosshead 78 by which the said roller is carried and consequently the piston-hammer 7, downwardly, to substantially the lower limit of the downward stroke; that is to say, until the roller 83 30 rolls under the extreme lower portion 315 of the upper cam portion 90. This downward movement of the piston will force any carbureted air in the chamber 5 outwardly through the carburetor 192 and thence through the pipe 35 up to the combustion cylinder 2 and when the upper end of the piston 8 has cleared the port 32, the air or explosive mixture, if there be one, will be delivered to the explosion chamber as soon as the piston 8 uncovers the port 32 of the explosive chamber. The continued rotation of the wheel 111 35 will cause the rollers 83 to ride up the incline 106 of the lower cam member 91 to the upper part 310 thereof. In so doing, air will be drawn into the chamber 5 past the valve 213 of the carburetor and through the bore 233 into the chamber 5, this lifting of the valve 213 from its seat permitting gasoline to flow 40 through the port 211 where it is mixed with the air drawn into the cylinder 5.

The upper movement of the piston 10 causes a rarefaction of the air in the chamber 6 and a consequent lifting of the valve 262 off 45 its seat to permit air to pass in through the

bell 268 of the deflector up into and past the valve 262 into the chamber 255 and thence through the port 246 into the chamber 6. This takes place throughout the upper outward movement of the piston-hammer under the manual rotation of the flywheel. At the 70 same time, the explosive mixture above the piston 8 is being compressed in the explosion chamber at the upper end of the section 2 by the piston 8. At or about the time the piston-hammer reaches the upward limit of its movement, the electric circuit is closed by the engagement of the projections 133 with the lower end of the slideable rod 134 and the consequent engagement of the contact points of the contact maker 117. If the explosive mixture above the piston is rich enough, the 75 spark will ignite it, the burning fuel will force the piston 8 and the parts carried thereby, down and the operation of the drill has 80 been started. Thereafter, at the end of every upward stroke, a fresh charge of explosive mixture will be ignited at the spark plug 29, the piston will be impelled downwardly, 85 rotating the rotor by reason of the engagement of the rollers 83 with the inclined portion 310 of the lower part or portion of the cam member 92. When the rollers 83 ride over the corner between the abrupt portion 312 and 90 311, the piston will be out of engagement with the cam and will be free to be impelled downwardly under the explosive force of the burning mixture in the cylinder at a constantly increasing speed until the lower end of the piston-hammer 10 shall engage the 95 strike-pin. Sufficient clearance is allowed between the lower end 15 of the upper cam portion and the lowest portion of the cam 91 after any rebound of the piston-hammer. It is for this reason that the portion 317 of the 100 upper cam member is abruptly cut away so as to provide sufficient space over the rollers for any rebound of the piston-hammer. After striking the blow, the momentum stored in the rotor, including the balance wheel 111, is 105 sufficient to continue to rotate the rotor at a considerable speed. This energy is sufficient to lift the piston-hammer to its upper position and compress the explosive mixture prior to ignition by the engagement of the rollers 82 with the slowly rising surfaces 106 of the 110 lower cam member 91.

When the piston-hammer is impelled downwardly, it compresses the fuel in the chamber 5 and when the upper end of the piston has cleared the port 32 it transfers the charge from the chamber 5 through and over the carburetor 192 through the pipe 35 and port 32 to the explosion chamber above the piston 8, driving the expanded gases of the 115 last downward working stroke outwardly through the ports 33 exactly on the principle of a two-cycle single-acting internal combustion engine. On every downward stroke, an 120 explosion is effected in the explosion chamber 125 130

ber and at the end of every downward stroke the spent gas is expelled from the combustion chamber by the admission of a fresh charge of explosive mixture.

5 The downward stroke of the piston-hammer compresses the air in the lower end 6 of the fuel intake and compression section 4. This compressed air is driven downwardly through the hole 63 in the strike-pin 62 which is in alinement with the hole through the drill and thus a comparatively strong blast of compressed air is driven on every stroke down through the strike-pin and down through the bore of the drill to the bottom of the hole 10 being drilled to expel detritus. The pressure to which air is so built up in the chamber 6 may be regulated and controlled by the pop valve shown in Figs. 8 and 9. On the 15 down stroke the pressure is high and the force 20 that is exerted against the end of the large piston 271 of the pop valve is greater than it is against the head of the valve 279 rigidly mounted on the same stem 272. When this 25 difference in effective pressure is greater than the force exerted by the spring 277, then the piston and valve and the parts carried thereby are pressed to the left (see Fig. 8) against the tension of the spring 277 to open or to open 30 a little wider the valve 279, thus permitting 35 more air to escape through the port 278. In this way the extent to which the pressure may be built up in the compression chamber 6 may be readily regulated and controlled to vary and regulate the force of the blow of the piston-hammer 10 on the strike-pin.

It will be observed that the carburetor is so constructed and arranged, as to the manner in which the air passes therethrough to the fuel mixing chamber and thence to the explosion end of the cylinder, that there can be no building up of the richness of the mixture during the operation of the device. As air is taken into the carburetor on the upward stroke of the piston-hammer it lifts the 40 valve 213 thereby permitting air and fuel to be intimately mingled on the way to the transfer chamber 5. On the working stroke, however, the valve 213 closes and thereafter no more fuel is mixed with the air and in traveling 45 from the fuel mixing chamber 5 to the explosion end of the cylinder, substantially all of the carbureted air is impelled over the valve 213 out to and through the transfer pipe 35. Substantially all the gaseous content 50 of the mixing chamber 5 is expelled on the downward stroke of the piston-hammer. The charge in the chamber 5 is a fresh charge on every upward movement of the piston-hammer and that charge is substantially completely transferred or impelled out of the cylinder 5 on each downward stroke of the piston-hammer. There is, therefore, substantially 55 no residue of explosive mixture left in the fuel mixing and transfer chamber 5 at the end of the transfer or downward

stroke and consequently the richness of the mixture in the chamber 5 does not increase as the machine continues to be operated.

In Fig. 25 I have shown a modification of my invention wherein the air compression chamber for compressing and delivering air to the bottom of the hole being drilled is omitted. In providing this modification, however, I have so planned and arranged it that the upper cylinder section 2 and the 70 rotor supporting section 3 will require no alteration or change whatever in size, arrangement or disposition. In other words with the cylinder parts 2 and 3 constructed and arranged as shown in Fig. 1, those parts 75 may be used without change to cooperate with a fuel intake and compression section 4 of 80 slightly different construction than that shown in Fig. 1.

In Fig. 25, the fuel intake and compression chamber is the chamber 6' below the impact end of the piston-hammer 10. The duct or port 223' communicating with the carburetor 192 is at the lower end of the chamber 6' just above the anvil 61. The chamber between 85 the piston-hammer 10 and the anvil 61 is omitted in those impact tools designed for drilling holes in stumps or for cutting pavement or for riveting. In this construction, the section 4' is provided at its upper end 90 with a flaring flange 57' adapted to fit snugly into the lower end of the intermediate portion 3 of the cylinder and between its ends is another upwardly extending flange terminating in the cylindrical portion 58' adapted 95 to fit into the large diameter at the extreme lower end of the intermediate portion 3 and horizontal flange 53' adapted to fit flat against the flange 50 at the end of the intermediate section for the passage of the clamping bolts 100 105 55 therethrough. As before, the lower end of the section 4' is provided with lugs 118 and bolts 172 for the attachment thereto of the lower ends of the frame member 170, which is slightly shorter than the frame shown in 110 Fig. 1. The operation of the mechanism shown in Fig. 25 insofar as the intake and transfer of the explosive mixture is concerned, is like that previously described in connection with Fig. 1 except that it is effected 115 by the piston-hammer 10 rather than by an intermediate piston-head 11 as shown in Fig. 1 and since the air compression chamber is omitted, the strike-pin 62 does not have an axial hole therethrough as in the form shown 120 in Fig. 1. The piston, however, is reciprocated exactly as it was reciprocated in a two-cycle single-acting combustion engine.

But the differences above pointed out between the construction shown in Fig. 1 and 125 that shown in Fig. 25, are practically the only distinctions between the two. In both embodiments of my invention, the delicate exposed portions of the mechanisms, such for instance as the carburetor, the gasoline sup-

ply pipe, the fuel transfer pipe, the electric unit and the timer, are all beneath or under the framework, by means of which the drill may be carried, guided and supported and between said framework and the outside of the cylinder. When the drill is not in use and is supported on this framework, the weight of the drill is not borne by any of the delicate or easily disarranged exposed portions. In both embodiments, the piston-hammer is impelled downwardly by the explosive force of the burning fuel and its speed on its forward stroke is not retarded prior to its impact with the strike-pin, except insofar as the pressure of a gas compressed on the working stroke, within the cylinder, may tend to regulate or modify the force of the blow.

Having thus described my invention, what I claim and desire to protect by Letters Patent of the United States is:

1. In an impact tool, the combination of a cylinder having three alined sections rigidly and separably secured together in alinement, a piston-hammer reciprocable therein on the principle of an internal combustion engine, said piston-hammer having a piston at one end reciprocating within the explosion section of said cylinder, with a crosshead extending radially from said piston-hammer and passing through guideway slots on opposite sides of the intermediate section of said cylinder, a piston at the other end of said piston-hammer forming the impact end of said piston-hammer and a piston between said crosshead and said hammer-head piston, said last two mentioned pistons being mounted to reciprocate in the impact end section of said cylinder, said impact end section being provided with two bores of different diameters, the bore of the section in which is the impact end of said piston-hammer being the smaller, a rigid piston rod connecting said three pistons and said crosshead rigidly together and a split cylindrical sleeve clamped around said piston rod between the two pistons adjacent the impact end of the piston-hammer, the space within said cylinder below the impact end of said piston-hammer being an air compression chamber and the space between said pistons operating as a fuel intake, mixing and transfer chamber, a carburetor communicating with said fuel intake and transfer chamber, and a conduit leading from said fuel intake and transfer chamber through said carburetor to the explosion section of said cylinder for transferring fuel from said transfer chamber to said explosion chamber of said explosion section at the end of the downward or working stroke of said piston-hammer.

2. In an impact tool, the combination with a cylinder and a piston-hammer reciprocable therein by the explosion of an explosive mixture and having two pistons at the impact end thereof spaced from each other a distance substantially equal to the length of the

stroke of said piston-hammer, the piston at the impact end of said piston-hammer being of smaller diameter than the other piston and the space between said pistons and the walls of the cylinder wherein said pistons reciprocate forming a fuel intake, mixing and transfer chamber, a piston rod connecting said two pistons, and removable means secured to said piston rod to limit the capacity of said intake and transfer chamber to the exact amount required to be transferred to the explosion end of said cylinder on each reciprocation of said piston-hammer.

3. In an impact tool, the combination of a main cylinder providing therein a cylindrical explosion chamber, a cylindrical fuel intake and mixing chamber and a cylindrical air compression chamber in axial alinement, a piston-hammer reciprocable in said cylinder and providing three pistons spaced from each other and rigidly secured to a common piston rod, the full length of said air compression chamber being substantially equal to the stroke of said piston-hammer and the full length of the fuel intake and mixing chamber being substantially the same as that of said air compression chamber, the diameter of said air compression chamber being substantially smaller than that of said fuel intake chamber, said fuel intake chamber and said air compression chamber being separated only by the piston at the impact end of said piston-hammer.

4. In an impact tool, the combination of a cylinder, a piston-hammer reciprocable therein on the principle of a two-cycle, single-acting motor, said cylinder comprising a separable lower end section having two alined bores of different diameters and of equal length, the bore nearest the explosion end of the cylinder being larger than the one at the impact end of said cylinder, said piston-hammer including two pistons rigidly connected together and fitting in and reciprocating in the two said bores of said lower section and a removable sleeve rigidly secured to the rod between said pistons to limit the fluid capacity of the space between said two pistons and the walls of said cylinders.

5. In an impact tool comprising a cylinder, a piston-hammer reciprocable therein on the principle of an internal combustion engine and a rotor impelled by said piston-hammer to rotate on said cylinder on an axis coincident with the axis of said cylinder, of a cover rigidly secured to said cylinder and disposed over and covering the top side of said rotor, two handles rigidly secured to said cover and substantially alined and extending outwardly on opposite sides of said tool to hold, steady and direct said tool in operating it and a rigid framework having its upper end secured to said cover and said handles and extending outwardly from said cylinder, then substantially parallel thereto and spaced

therefrom and then inwardly towards said cylinder, means to rigidly attach the lower end of said framework to the lower end of said cylinder, an ignition unit and a contact device mounted on said cover and extending under said framework, and a carburetor mounted on said cylinder and positioned between said cylinder and said framework, said framework being operative to support the tool horizontally and to protect said ignition unit, said contact device and said carburetor from injury.

6. In an impact tool comprising a cylinder, a piston-hammer reciprocable therein on the principle of an internal combustion engine and a rotor impelled by said piston-hammer to rotate on said cylinder on an axis coincident with the axis of said cylinder, of a cover rigidly secured to said cylinder and disposed over and covering the top side of said rotor, two handles rigidly secured to said cover and substantially alined and extending outwardly on opposite sides of said tool to hold, steady and direct said tool in operating it and a rigid framework having its upper end secured to said cover and said handles and extending outwardly from said cylinder, then parallel thereto and spaced therefrom and then inwardly towards said cylinder, means to rigidly attach the lower end of said framework to the lower end of said cylinder, a liquid fuel tank mounted on the top of said framework, a carburetor mounted on said cylinder and a liquid fuel supply pipe connecting said tank with said carburetor, and a transfer pipe leading from said carburetor to the explosion end of said cylinder, said carburetor and said pipes being positioned between said framework and said cylinder.

7. In a drill, the combination with a cylinder, a reciprocable piston-hammer therein operated on the principle of an internal combustion engine, said cylinder comprising a top explosion end, a bottom impact end, and an intermediate rotor section, a rotor mounted on said intermediate section to rotate on an axis coincident with that of said cylinder and driven by said piston-hammer, a cover rigidly mounted on said top explosion end of said cylinder and covering substantially the top of said rotor and provided with a pocket for an ignition unit, a pocket within which steadyng handles may be secured and a pocket for a contact device of the ignition system of said drill.

8. In an impact device, the combination of a cylinder, comprising three alined cylindrical sections rigidly secured together, the upper section being an explosion cylinder, a piston-hammer reciprocable therein, a rotor mounted on said cylinder to rotate on an axis coincident with the axis of said cylinder, a cover rigidly secured to said cylinder adjacent the lower end of said upper section and substantially enclosing the top side of

said rotor, bolts accessible from above said cover to secure said upper cylinder section to the adjacent section whereby said upper section is removable from said adjacent section by the withdrawing of said bolts without removing said cover, and a pair of handles extending outwardly horizontally from the opposite sides of said cover and rigidly secured to said cover.

9. In an impact tool, the combination of a cylinder having three sections rigidly secured together in alinement, a piston-hammer having a piston at one end reciprocating within the explosion section of said cylinder, with a cross-head extending radially from said piston-hammer and passing through guide way slots on the opposite sides of the intermediate section of said cylinder, a piston at the other end of said piston-hammer, forming the impact end of said piston-hammer and a piston between said cross-head and said last mentioned piston, said two last mentioned pistons being mounted to reciprocate in the impact end section of said cylinder, said impact end section being provided with two bores of different diameters, the bore of the section in which is the impact end of said piston-hammer being the smaller, means surrounding said piston-hammer between said pistons adjacent the impact end of said piston-hammer to make the volumetric capacity of the larger bore that of a charge of explosive mixture at substantially atmospheric temperature, a carburetor communicating with said second or larger bore forming the fuel intake and transfer chamber and a conduit leading from said chamber through said carburetor to the explosion section of said cylinder for transferring fuel to said explosion section at the end of the working stroke of said piston-hammer.

10. In a portable impact tool, the combination with a cylinder and a piston-hammer reciprocable therein by the explosion of an explosive mixture, having two pistons at the impact end thereof spaced from each other a distance equal to the length of the stroke of said piston-hammer, the piston at the impact end of said piston-hammer being of smaller diameter than the said other piston and the spaces between said pistons and the walls of said cylinder, wherein said pistons reciprocate, forming a transfer chamber, and means connecting said two pistons and limiting the capacity of said intake and transfer chamber to the exact amount required to be transferred to the explosion end of said cylinder on each reciprocation of said piston-hammer.

11. In an impact tool, a cylinder, a piston-hammer reciprocable therein on the principle of an internal combustion engine, said piston-hammer having a piston at one end reciprocable within the explosion section of said cylinder, two pistons adjacent the opposite end of said piston-hammer, the last two mentioned

- pistons being mounted to reciprocate in the impact end of said cylinder, said impact end of said cylinder being provided with two coaxial bores of different diameters, the bore at the lower end being the smaller and being in direct open communication with the adjacent end of the larger bore, means extending between said pistons at the impact end of said piston-hammer and of a size to enter the smaller of said bores as said piston-hammer advances on its working stroke, to substantially reduce the volumetric capacity of said larger bore, the space within said cylinder between said pistons operating as a fuel intake and transfer chamber and being provided with a port, a carburetor communicating with said intake and transfer chamber through said port, and a conduit communicating with said port through said carburetor to the explosion section of said cylinder at the end of the downward or working stroke of said piston-hammer. 70 75
12. In an impact tool, the combination with a cylinder and a piston-hammer reciprocable therein by the explosion of an explosive mixture, said cylinder having two aligned cylinder sections of different bores at the impact end thereof, two pistons of said piston-hammer respectively fitting said bores and spaced from each other a distance substantially equal to the length of the stroke of said piston-hammer, the cylinder at the impact end of said piston-hammer being of smaller diameter than the other cylinder in said cylinder section and being in direct open communication with the adjacent end of the larger bore thereof, the space between said pistons and the walls of said cylinder wherein said pistons reciprocate forming a fuel intake, mixing and transfer chamber, means rigidly connecting said two pistons and filling a substantial portion of the spaces therebetween and of a size to freely enter said smaller cylinder on the working stroke of said piston-hammer to limit the effective capacity of said intake and transfer chamber to substantially that amount of explosive mixture which is required to be transferred to the explosion end of said cylinder on each reciprocation of said piston-hammer. 80 85 90 95 100 105 110 115
13. In an impact tool, the combination of a cylinder, a piston-hammer reciprocable therein on the principle of a two-cycle, single-acting combustion motor, said cylinder comprising a lower section having two aligned bores of different diameters and of equal length, the bore nearest the explosion end of said cylinder being larger than the one at the impact end of said cylinder and being in direct open communication with the adjacent end of said smaller bore, said piston-hammer including two pistons fitting and respectively reciprocating in said two bores of said lower section respectively, and means rigidly secured to the piston-hammer between 120 125 130

In witness whereof, I have hereunto set my hand this twelfth day of July, 1927.

LIONEL A. SCHMIDT.
